UNITED STATES PATENT OFFICE.

ESSEX L. LOMAX, OF WASHINGTON, DISTRICT OF COLUMBIA.

CHURN.

1,320,881.

Specification of Letters Patent.

Patented Nov. 4, 1919.

Application filed July 3, 1918. Serial No. 243,125.

To all whom it may concern:

Be it known that I, ESSEX L. LOMAX, a citizen of the United States, residing at Washington, in the District of Columbia, 5 have invented certain new and useful Improvements in Churns, of which the following is a specification.

This invention relates to the class of agitators, and more particularly to novel and 10 useful improvements in churns.

The invention relates more specifically to rotary churns, and to that class in which the rotating blades, of which there are two in 15 number, rotate in opposite directions so as to give sufficient agitation and expedite the churning operation, the blades being constructed in a novel manner for the purposes mentioned.

With the above and other objects in view, 20 as will appear as the description proceeds, the invention comprises the various novel features of construction and arrangement of parts which will be more fully described herein and set forth with particularity in 25 the claim appended hereto.

Reference is had to the accompanying drawings forming a part of this application, in which like reference characters indicate the corresponding parts throughout the 30 several views, in which

Figure 1 is a vertical sectional view of an improved churn constructed in accordance with my invention,

Fig. 2 is a horizontal sectional view taken 35 through the churn blades, and

Fig. 3 is an enlarged detail sectional view showing the manner of securing the outer churn blade in position.

Referring to the drawings in detail, the 40 numeral 10 indicates a container, preferably in the form of a glass jar having a screw top 11 upon which the operating mechanism is supported and adapted to operate through a central opening 12 therein. Arranged 45 upon this cap is a frame 13 having journaled horizontally therein a shaft 14 provided with a suitable operating handle 15 on its outer end.

At the inner end of the shaft 14 there is 50 secured a large bevel gear 16 meshing with upper and lower bevel gears or pinions 17 and 18 respectively. The gear 17 is fixed to a shaft 19 rotatably journaled in the bearing part 20 of the frame and in the upper 55 part of the latter, suitable means being provided to support the shaft against displace-

ment. The shaft extends through the lower portion of the frame and through the opening 12 into the jar or container 10 and has engaged thereon a tubular shaft 21, to the 60 upper end of which the gear 18 is fixed, so that the gears 17 and 18 will mesh with the gear 16 at diametrically opposite points of the latter, so as to be driven in opposite directions.

The dasher construction which comprises the particular novel feature of my invention, consists of an outer blade 22, having the upper end thereof split centrally and vertically thereof and received within opposite bifurcations 23 of a casting or the like 24 secured to the lower end of the tubular shaft 21. This blade is also provided with a tapered upper end produced by inclined side portions 25, the upper end of the 75 blade 22 being thus tapered for attachment as specified, and provided with a similarly shaped central opening 26. The opening 26 terminates short of the bottom, so as to provide a transverse connecting strip 27, 80 while the opposite edges of the blade 22 are curved in opposite directions, as shown at 28, and provided with adjacent series of openings 29 vertically arranged.

Received within the opening 26 is an inner blade 30, the same corresponding in shape to the outer blade and the opening 26 and being spaced from the inner edge walls of the opening 26 and having its upper tapered end secured to the split lower end of 90 of the shaft 19, as shown at 31. This blade 30 has its opposite vertical edges curved in opposite directions as shown at 32, the curvature thereof being opposite to that of the curvature of the portions or vertical 95 edges 28 of the outer blade 22, thus causing the curved portions of the inner blade to throw the fluid against the curved portions of the outer blade, which latter will impart opposite motion or agitation thereto, to accomplish the churning operation efficiently and expeditiously. The tapered or beveled 100 formation of the upper ends of the blades also prevents the splashing of the contents of the jar against the cover thereof, or from being forced out through the openings receiving the shafts, and obviates a disadvantage in connection with the old construction of blades.

From the foregoing description taken in 110 connection with the accompanying drawings, it is thought that a clear and compre-

hensive understanding of the construction, 5 operation, and advantages of my invention may be had, and while I have shown and described the device as embodying a specific structure, I desire that it be understood that such changes may be made in said structure as do not depart from the spirit and scope of the invention as claimed.

Having thus described my invention, 10 what I claim as new and desire to secure by Letters Patent, is:

The combination in a churn of a tubular shaft extending therein, a second shaft extending through the tubular shaft into the 15 churn, means for imparting opposite rotation to the shafts, an outer blade formed of a flat plate connected with the tubular shaft

and provided with oppositely curved outer side edges and with series of openings adjacent each outer side edge, said outer blade having a portion thereof between its side edges and above the lower edge cut out to receive an inner blade formed of a flat plate conforming to the contour of said cut out portion, and positioned therein and connected with the second shaft, said inner blade having its side edge portions curved in opposite directions and opposite to the direction of curvature of adjacent side edges of the first mentioned blade. 20 25 30

In testimony whereof, I affix my signature hereto.

ESSEX L. LOMAX.
